(57) **CLAIM**

The ornamental design for a beverage brewer display screen or portion thereof with animated graphical user interface, as shown and described herein.

DESCRIPTION

FIG. 1 is a front view of a first image in a sequence for a beverage brewer display screen, or portion thereof, with an animated graphical user interface.

FIG. 2 is the second image of the sequence.

FIG. 3 is the third image of the sequence.

FIG. 4 is the fourth image of the sequence.

FIG. 5 is the fifth image of the sequence.

FIG. 6 is the sixth image of the sequence.

FIG. 7 is the seventh image of the sequence.

FIG. 8 is the eighth image of the sequence.

FIG. 9 is the ninth image of the sequence.

FIG. 10 is the tenth image of the sequence.

FIG. 11 is the eleventh image of the sequence; and,

FIG. 12 is the twelfth image of the sequence.

The appearance of the animated user interface sequentially transitions between the images shown in FIGS. 1-12. The process or period in which one image transitions to another forms no part of the claimed design. The broken line showing of the display screen and portions of the animated graphical user interface are included for the purpose of illustrating portions of the article and form no part of the claimed design.

1 Claim, 12 Drawing Sheets
